[57] CLAIM

The ornamental design for a barbecue grill cleaner, substantially as shown and described.

DESCRIPTION

FIG. 1 is a perspective view of a barbecue grill cleaner, showing my new design;

FIG. 2 is an enlarged right end elevational view thereof;

FIG. 3 is an enlarged left end elevational view thereof;

FIG. 4 is an elevational view taken from the top of FIG. 2;

FIG. 5 is an elevational view taken from the bottom of FIG. 2;

FIG. 6 is an elevational view taken from the right of FIG. 2;

FIG. 7 is an elevational view taken from the left of FIG. 2;

FIG. 8 is a perspective view of a second embodiment of a barbecue grill cleaner;

FIG. 9 is an enlarged right end elevational view thereof;

FIG. 10 is an enlarged left end elevational view thereof;

FIG. 11 is an elevational view taken from the top of FIG. 9;

FIG. 12 is an elevational view taken from the bottom of FIG. 9;

FIG. 13 is an elevational view taken from the right side of FIG. 9;

FIG. 14 is an elevational view taken from the left side of FIG. 9.
